UNITED STATES PATENT OFFICE

118,274

DESIGN FOR A SLICING KNIFE

William H. Barry, Bridgeport, and William O. Stauffer, Fairfield, Conn., assignors to Remington Arms Company, Inc., a corporation of Delaware

Application April 5, 1939, Serial No. 84,046

Term of patent 14 years

To all whom it may concern:

Be it known that we, William H. Barry and William O. Stauffer, citizens of the United States, residing, respectively, at 773 Connecticut Avenue, Bridgeport, county of Fairfield, State of Connecticut, and 180 North Benson Road, Fairfield, county of Fairfield, State of Connecticut, have invented a new, original, and ornamental Design for a Slicing Knife, of which the following is a specification, reference being had to the accompanying drawing, forming part thereof.

In the drawing:

The essential features of our design for a knife, as shown, reside in the configuration of the handle in combination with the ornamentation as applied thereto.

We claim:

The ornamental design for a slicing knife, as shown and described.

WILLIAM H. BARRY.
